[57] **CLAIM**

The ornamental design for a bottle, as shown and described.

DESCRIPTION

FIG. 1 is a top, front and left side perspective view of a bottle showing our new design;

FIG. 2 is a top plan view thereof;

FIG. 3 is a front elevational view thereof;

FIG. 4 is a right side elevational view thereof, the opposite side being a mirror image;

FIG. 5 is a rear elevational view thereof;

FIG. 6 is a bottom plan view thereof; and,

FIG. 7 is a top, front, and left side perspective view of the bottle showing the unclaimed cap in the exploded condition, the top, rear and right side perspective view of the bottle is the same.

The broken line showing of the cap is for illustrative purposes only and forms no part of the claimed design.
